UNITED STATES PATENT OFFICE.

JOHN C. WAHL, OF CHICAGO, ILLINOIS, ASSIGNOR TO THE WAHL COMPANY, OF WILMINGTON, DELAWARE, A CORPORATION OF DELAWARE.

CALCULATING-MACHINE.

1,311,730.

Specification of Letters Patent. Patented July 29, 1919.

Application filed August 20, 1917. Serial No. 187,108.

To all whom it may concern:

Be it known that I, JOHN C. WAHL, a citizen of the United States, residing at Chicago, in the county of Cook and State of Illinois, have invented certain new and useful Improvements in Calculating-Machines, of which the following is a specification.

My invention is an improvement in totalizers for use with typewriter calculating machines, and particularly has for its object the provision of a totalizer which will calculate in the long ton table. This table is extensively used in maritime shipping and is as follows:

15 Twenty-eight pounds equal one quarter.
Four quarters equal one hundred weight.
Twenty hundred weight equal one long ton.

It will be observed that in this table the 20 numbers are to four different bases. The tons are to the base 10, the hundred weight are to the base 20, the quarters are to the base 4 and the pounds are to the base 28.

It is possible to handle quantities in the first 25 three of these bases on the Wahl totalizer as ordinarily made, since quantities to the base 10 are handled in the regular money totalizer; quantities to the base 20 are handled in the Wahl type of English totalizer by the 30 expedient of making one denomination carry every tenth step and the next higher combination carry every second step. The combination of the two wheels will thus calculate to the base 20. Calculations to the base 35 4 are easily accomplished in a Wahl totalizer which calculates Indian currency, one denomination of which is to the base 16. Therefore, handling numbers to the base 4 may be accomplished by using a wheel used 40 to calculate to the base 16 and providing a carrying tooth at every fourth step. However, handling the base 28 offers peculiar difficulties, for the reason that the number of steps, viz., twenty-eight, is entirely too 45 large to be accommodated on a single number wheel of a Wahl totalizer and therefore it would be necessary to divide the units, that is, show the figure denoting the 10's on one wheel, and figures denoting the units on another wheel. But this course again leads to 50 difficulties for the reason that the units wheel will have to carry at some space when it passes from 9 to 0, e. g., in passing from 9 to 10, or 19 to 20, and this same wheel at 55 other places will have to carry between the

seventh and eighth steps, e. g., as when it passes from 27 to 0. These two requirements are contradictory and I have accordingly solved this complicated problem by the expedient of making a number wheel with 60 fourteen steps, having two sets of numbers thereon, from 0 to 13 in one row, and from 14 to 27 in another row, and providing a shiftable shutter which operates in a cycle of two steps and is arranged to expose the 65 rows alternately. From the above it will be apparent that the object of my invention is the provision of an efficient and simple totalizer which will calculate weights expressed in the long ton table and which is 70 particularly applicable to be used with the well-known Wahl adding machine.

My invention will be best understood by reference to the following figures, of which

Figure 1 is a section through my improved 75 totalizer;

Fig. 2 is a partial plan section along the line 2-2 of Fig. 1;

Fig. 3 is a section along the line 3-3 of 80 Fig. 1;

Fig. 4 is a perspective view of the shutter-operating cam, and

Fig. 5 is a development of the number 85 wheels.

There are a large number of parts in my 90 invention which have already been described in many applications, particularly in my issued Patent No. 893,719, issued July 21, 1908. It will not be necessary to describe these parts in this specification and 95 I shall therefore confine my description to the parts which are peculiar to my present invention. The totalizer, a section of which is shown in Fig. 1, is mounted on a truck 10, which travels with the typewriter carriage in the manner described in my cited patent. Numbers are inserted into the totalizer by a master wheel 11, which is mounted on a shaft 12, which rotates in the framework of the machine a differential 100 amount as the numeral keys, not shown, are operated. A master dog 13 serves to unlock the carrying chain of the totalizers prior to the insertion of each digit of the numbers, the cycle of action being that the 105 master dog 13 rotates on its axis 14 in a counter-clockwise direction, the master wheel 11 rotates a number of steps proportional to the digit which is inserted, then the master dog 13 returns to its original 110

position. This cycle of action is the customary cycle of the Wahl machine and need not be further described. The totalizer is supported between side plates 15 and 16, 5 which are held together by suitable pillars and serve to support a series of shafts rotatably mounted on which are the various gears of which the totalizer is composed. The totalizer side plates serve to support a 10 shaft 17, on which are rotatably mounted the totalizer gears 30 to 37 inclusive, all of which are adapted to engage with the master wheel 11. A shaft 18, rigid in the side plates, serves to support a set of intermediate gears 19, which are rotatably mounted thereon and serve to transmit the motion of the totalizer gears to a set of number wheels 20 to 27 inclusive, which are rotatably mounted on a shaft 28, held between the side plates. The carrying gears 38 and 39, which are mounted on studs 40 and 41 in swinging arms 42 and 43 rotatably mounted on shafts 44 and 45, rigid in the side plates 15 and 16, serve to transmit 25 the motion of the wheel of lower order to that of higher order when the wheel of lower order has turned through a complete cycle. The carrying mechanism is, except for some slight modifications as to carrying 30 in a cycle other than 10, the same as that described in the totalizer of the cited patent.

The gear arrangement of my improved totalizer may be best understood by referring to Fig. 5, in which is shown a development 35 of the various number wheels constituting the totalizer. The first four number wheels 20, 21, 22 and 23 have ten steps and are actuated by totalizer gears 30, 31, 32 and 33, all of thirty teeth each and provided with three carrying points. The four wheels, 20 to 23 inclusive, will, therefore, carry in a cycle of ten.

The next two wheels 24 and 25 have the numbers arranged as shown in Fig. 5. The 45 wheel 24 carries every second step and the wheel 25 carries every tenth step. Both wheels are driven by totalizer gears 34 and 35, of thirty teeth each. Wheel 34 has fifteen carrying teeth and wheel 35 has 50 three carrying teeth. The totalizer gear 36 has thirty-two teeth and eight carrying teeth. It, therefore, carries every fourth step. The number wheel 26, in mesh with the totalizer gear 36, has eight steps and 55 has its numbers arranged in two groups containing four numbers each. The totalizer gear 37 is composed of two distinct gears of fourteen teeth each and these gears are united by an idle gear 46, (Fig. 2) 60 which is mounted on one of the swinging arms 42. This is for the purpose of making the two gears 37 revolve as a single unit when driven from the extreme righthand gear, but providing a means of disconnection of the two units when the gear 37

is actuated in the tens decimal order since at that time the gear 46 is lifted out of its meshing engagement with the two wheels by the action of the master dog 13. Reference to Fig. 5 will show that the number 76 wheel 27, in mesh with and driven by the gear 37, has two sets of numbers from zero to thirteen and from fourteen to twenty-seven, said numbers being arranged in two parallel rows. The number wheel 27 is 75 provided with fourteen teeth.

The totalizer is provided with a cover 47, having a sight window 48 therein, and between said window and the number wheel 27 is a shutter 49, which is rotatably mounted on the shaft 28 and has therein a window 50 adapted to display the numbers in the row headed 14 in the wheel 27 and a window 51 which is adapted to display the numbers in the row headed zero in said 85 wheel. The shutter is actuated by means of a slot 51' in the sides thereof, engaging in which is a pin 52, mounted on a rocker 53, rotatably mounted on the shaft 18 and provided with pallets 54 and 55, which are 90 adapted to be actuated by the cams 56 and 57 on the lefthand wheel 37. The cams 56 and 57 are so arranged that the shutter is changed to bring the window 50 or 51 opposite the sight opening 48 at every fourteenth step of the totalizer wheels 37. Thus one or the other of the two sets of numbers on the number wheel 27 are alternately exhibited.

As before noted, the actuator employed 100 with my improved totalizer is of the standard Wahl form, with the exception that it is of the peculiar variety or species known as the "Sterling" actuator. In this actuator there is provided a key, which, when actuated, 105 will print "1" and rotate the master wheel 11 ten spaces. This key is used in entering numbers in the denomination of pounds. For instance, if it were desired to enter thirteen pounds, this special key would 110 be operated in the tens place, thus rotating the left hand wheel 37 ten spaces and print a "1" on the worksheet in the tens place. The 3-key would next be operated, with the result of rotating the righthand wheel 37 115 three spaces and printing a "3" on the worksheet to the right of the previously printed "1." Thus the number "13" would be printed on the worksheet and entered in the totalizer. 120

The insertion of a number of pounds such as 25 is accomplished in the following manner: The special key previously referred to is provided to print a "2" in its shift position. To insert 25 pounds into the totalizer, 125 it is necessary to bring the totalizer to a position in which the lefthand wheel 37 is in mesh with the master wheel 11. The platen is then thrown to its shift position, and the special key is operated. This will 130

print "2" on the worksheet and insert "10" in the totalizer. The typewriter carriage is back-spaced and the special key operated again in its shift position. This will result in printing a second "2" on the worksheet and again inserting 10 into the totalizer. Since, however, this second 2 is superimposed on the 2 previously printed, the two impressions will appear as one and 20 will have been inserted in the totalizer as a result of the two operations of the 10-key. The 5-key is then operated, with the result that 5 will be printed on the worksheet to the right of the previously printed 2, and 5 will be inserted into the totalizer. As a result of these operations there will be 25 printed on the worksheet and 25 entered in the pound denomination of the totalizer.

20. It will be obvious to those skilled in the art that my herein described structure is capable of many modifications and that the principle of having two sets of numbers on a number wheel and having a shutter shiftable to exhibit one or the other of the two sets may be extended to totalizers calculating tables other than the precise table which is calculated by my totalizer herein described. However, such changes and modifications will be apparent to those skilled in the art and I do not wish to be limited to the precise structure herein described, since I claim:

1. In a totalizer, the combination of a number wheel having a plurality of sets of figures arranged in rows, the highest figure in one row being less than the lowest figure in a second row, a sight opening through which said figures may be viewed, and a shiftable shutter having two alternate positions and arranged to display figures in one or the other of said rows.

2. In a totalizer, the combination of a number wheel having thereon numbers arranged in two rows, the highest number in one row being less than the lowest number in the other row, an oscillating shutter co-operating with said number wheel, open-

ings in said shutter adapted to display figures in one or the other of said rows, and means to oscillate said shutter when the highest number on said number wheel has been exhibited.

3. In a totalizer, the combination of a number wheel arranged to operate in a cycle of fourteen steps, two sets of numbers on said wheel, said numbers being arranged from zero to thirteen and from fourteen to twenty-seven, a shutter co-operating with said number wheel, said shutter having two windows therein, each window being adapted to exhibit one or the other of said sets of numbers, means to shift said shutter in one direction coincident with the passing of the number wheel from its thirteenth to its fourteenth step, and means to restore it to its original position on the passage of said number wheel from its twenty-seventh to its twenty-eighth step.

4. In a calculating machine, the combination of a totalizer, a number wheel therein, said wheel having thereon numbers arranged in two rows, an oscillating shutter co-operating with said number wheels, said shutter having openings adapted to display figures in one or the other of said rows, a gear to enter numbers in said number wheel, and a cam revolving synchronously with said gear and arranged to shift the shutter so as to display one or the other of said rows of figures.

5. In a calculating machine, the combination of a totalizer, a number wheel therein, said wheel having thereon numbers arranged in two rows, an oscillating shutter co-operating with said number wheels, said shutter having openings adapted to display figures in one or the other of said rows, a gear arranged to operate said number wheel, a cam rigid to said gear, and means operated by said cam to shift said shutter to alternate positions.

In witness whereof I have hereunto subscribed my name.

JOHN C. WAHL.
